United States Patent Office

Des. 193,185
Patented July 10, 1962

193,185

PERFORATING MACHINE

Hans Elsner, Wilhelmshaven, Germany, assignor to
Olympia Werke A.G., Wilhelmshaven, Germany

Filed Oct. 12, 1960, Ser. No. 62,455

Term of patent 14 years

(Cl. D26—5)

Fig. 1.

Fig. 2.

Fig. 3.

FIG. 1 is a perspective view of a perforating machine, showing my new design as seen from one side;

FIG. 2 is a perspective view seen from another side; and

FIG. 3 is a perspective view from the rear of the perforating machine.

The essential features of the design reside in the portions shown in full lines on the drawing.

I claim:

The ornamental design for a perforating machine, as shown and described.
